DESIGN FOR A BOOK HOLDER

William P. Baham, Baton Rouge, La.

Application June 27, 1945, Serial No. 120,360

Term of patent 3½ years

(Cl. D33—1)

To all whom it may concern:

Be it known that I, William P. Baham, a citizen of the United States, residing at Baton Rouge, in the parish of East Baton Rouge and State of Louisiana, have invented a new, original, and ornamental Design for a Book Holder, of which the following is a specification, reference being had to the accompanying drawing, forming part thereof.

I claim:

The ornamental design for a book holder, as shown.

WILLIAM P. BAHAM.
